WEDGE-SHAPED FREE-FALL DEVICE

BACKGROUND OF THE INVENTION

This invention relates to free-fall device and more particularly to a free-fall device having a wedge-shaped body which will cause the body to autorotate and glide when free falling through the air.

When a spinning body, such as a baseball, moves through the air it generates a force which is perpendicular to its direction of motion and to the axis of spin. This force is called Magnus force or Magnus lift. In addition, if the falling body has flutes or vanes which produce a torque about its center of gravity while moving through the air, the body has the ability to spin itself and is said to "autorotate." When an autorotating body is falling free through the atmosphere, its spin generates Magnus lift and causes the body to glide at an angle from the vertical which is equal to the arctangent of the lift force divided by the drag force.

In recent years, this concept has been utilized in the manufacture of aerial mines or bomblets. Generally, a plurality of the bomblets are placed in a canister or the like and the canister dropped from an aircraft. After a predetermined amount of time, the canister opens and permits the plurality of bomblets to free-fall. The inherent ability of the bomblets to autorotate provides a random ground impact pattern over a large area.

Many different autorotating shapes have been used over the years. Many shapes do not lend themselves to high packaging density in the respective canister or dispenser. It is of the utmost importance that the maximum number of bomblets are incorporated in any given canister in order to provide maximum bomblet density in the impact area.

Accordingly, it is an object of this invention to provide a free-fall device which will autorotate and hence glide, and has the added advantage of being efficiently packaged.

Another object of this invention is to provide a wedge-shaped free-fall device having aerodynamic means for causing the device to autorotate.

A further object is to provide a free-fall device having an outer shape which lends itself for ease of manufacture and provides high packaging density for a given canister or dispenser.

SUMMARY OF THE INVENTION

This invention provides an improved free-fall device having a generally wedge-shaped body with aerodynamic flutes thereon to cause the device to autorotate. The flutes are disposed about the periphery of the device to induce spin of the device about an axis of rotation which passes through the center of gravity of the device. The flutes are all situated in the same direction about the axis of rotation in order to produce rotational moments in the same direction.

Other details of this invention will become apparent as the following description of the exemplary embodiment hereof presented in the accompanying drawings proceeds.

BRIEF DESCRIPTION OF THE DRAWINGS

The accompanying drawings show a present exemplary embodiment of this invention in which:

FIG. 1 is a perspective view illustrating one exemplary embodiment of this invention;

FIG. 2 is a top view of the free-fall device of this invention;

FIG. 3 is a side view of the free-fall device of this invention;

FIG. 4 is an end view of a free-fall device of this invention; and

FIG. 5 is a free body diagram of the device of this invention.

DESCRIPTION OF THE ILLUSTRATED EMBODIMENT

Reference is now made to the drawings which illustrate an exemplary embodiment of an improved free-fall device or bomblet of the present invention which is designated generally by the reference numeral 10. The free-fall device 10 has a

housing or casing substantially wedge-shaped and generated by an isosceles triangle. The triangular faces of the device 10 are generally designated as 12 and 14 and define substantially rectangular shaped end surfaces 16 and 18 and a substantially rectangular shaped bottom surface 20.

Along all edges of the triangular faces 12 and 14 are aerodynamic elements such as flutes, vanes and the like. The flutes are all aerodynamically situated in the same direction about an axis of rotation or spin axis 22 in order to produce autorotation of the free-fall device 10 in the same direction. The spin axis 22 is seen to lie on the center of gravity of the device 10 and is parallel to the surfaces 12, 14 and 20.

The triangular face 14 has a flute 24 along the long or unequal side of the triangle and a flute 26 along each of the short or equal sides of the triangular face. Likewise, triangular face 12 has a flute 28 along the long or unequal side of the triangular face and a flute 30 along the short or equal sides of the triangular face. It may be seen that each respective flute has a reaction surface which for purposes of explanation will be designated by the same reference numeral followed by the letter designation "A." As best seen in FIGS. 1 and 4, the free-fall device 10 has reaction surfaces 24A, 26A, 28A and 30A. Hence, when the free fall device 10 is in the free-fall state, the reaction surfaces respond or react with the resistance of the air to cause the device 10 to spin or autorotate about the axis 22 which causes the device 10 to glide at an angle θ from the vertical. As seen in the free body diagram of FIG. 5, as the free-fall apparatus 10 spins or autorotates, it generates a Magnus lift and glides at an angle θ from the vertical where

$$\theta = \arctan (\text{Lift Force}/\text{Drag Force})$$

In operation, a plurality of the free-fall device 10 are packaged in a suitable canister or dispenser which will be discharged from an aircraft or the like. The canister will open 35 a predetermined time after discharge from the aircraft or the like to permit each individual device 10 to autorotate in order to provide maximum ground impact patterns.

It can be seen that this invention provides a free-fall device which, because of its geometric wedge-shaped configuration, permits high packaging density. The shape of the free-fall device of this invention also lends itself for ease of manufacture.

While a present exemplary embodiment of this invention has been illustrated and described, it will be recognized that this invention may be otherwise variously embodied and practiced by those skilled in the art.

What is claimed is:

1. In a free-fall device adapted for release from a canister having a plurality of such devices contained therein, the improved free-fall device comprising:

a housing having a geometric profile defined as a prism generated by lateral movement of an isosceles triangle, said housing having opposing triangular faces; and reaction means along the edges of the triangular faces of the housing to cause the device to spin about an axis of rotation when the device is in free-fall.

2. A free-fall device comprising:

a housing having a generally wedge-shaped isosceles prism configuration, said housing having parallel triangular faces defining generally rectangular surfaces between the short sides of the triangular faces and a generally rectangular surface between the long sides of the triangular faces; and

aerodynamic means located on all edges of the triangular surfaces providing reaction surfaces in order to produce autorotation of the device about an axis of rotation in free-fall.

3. A free-fall device as set forth in claim 2 in which the aerodynamic means further comprises flutes along the edges of the triangular faces, said flutes being situated in the same direction about the axis of rotation to produce autorotation in the same direction; said device being further defined by the axis of rotation being parallel to the triangular faces and to the long side of the triangular faces.

4. A free-fall device as set forth in claim 3 in which the axis of rotation lies on the center of gravity.
5. In a free-fall device adapted for release from a canister having a plurality of such devices contained therein, the improved free-fall devices comprising:
- a housing having a generally wedge-shaped configuration, said housing having opposing triangular faces defining a generally rectangular surface between the respective sides of the triangular faces; and aerodynamic flutes located on all edges of the triangular 10

surfaces, said flutes being situated in the same direction and providing reaction surfaces to produce autorotation of the device about an axis of rotation in free-fall.

6. A free-fall device as set forth in claim 5 in which the opposing triangular faces are isosceles triangular faces, said device being further defined by the axis of rotation being parallel to the triangular faces and to the long side of the triangular face and the axis of rotation lies on the center of gravity.
